VARIABLE FACE CAM

Henry Devlin, Saginaw, Mich., assignor to Baker Perkins Inc., Saginaw, Mich., a corporation of New York

Application June 9, 1941, Serial No. 397,278

2 Claims. (Cl. 74—567)

This invention relates to variable cams in which a cam follower is selectively directed through alternative cam tracks to impart variable motion to mechanism driven by the cam follower, and has for its object the provision of a continuously driven face cam having communicating circular and eccentric tracks, together with switch mechanism for directing the cam follower selectively into one track or the other. The switch mechanism of my novel cam is actuated during rotation of the cam by engaging a movable abutment member, which member is selectively moved to or from switch-changing position by any suitable part of the machine with which the cam action is to be co-ordinated. This improved cam has the advantage over drum cams heretofore employed for this general purpose that it occupies no more space than a conventional cam, and may be installed in many existing machines having fixed cams with little or no alteration of the machine. Where a drum cam is used the machine frame and drive mechanism ordinarily must be designed especially to accommodate it.

An application of the cam of this invention to a specific machine is described and illustrated in my copending application for improvements in dough dividers, Serial No. 346,176, filed July 18, 1940, of which this present application is a continuation-in-part.

A cam embodying the features of the invention is illustrated in the accompanying drawings, showing the switching mechanism in different positions, in which—

Fig. 1 shows one form of the cam and its follower mechanism, the cam follower leaving the inner eccentric cam track;

Fig. 2 shows the follower in the outer circular track about to be intercepted and directed into the inner track; and

Fig. 3 shows a modified cam also embodying the invention having its eccentric track outside of its circular idling track.

Referring to Figures 1 and 2, a cam 28, which rotates counter-clockwise, has a circular outer track 35 and an eccentric inner track 36. Track 36 communicates at both ends with track 35. A cam roller 27 journaled on a rocker-arm 26 rides in the tracks and is actuated by the eccentric track to rock a lever arm 25 of an associated mechanism for any desired purpose, in known manner. The lever arm is actuated at desired periods by the operation of the switch mechanism to direct the cam roller 27 through the eccentric track 36. When the switch mechanism directs the cam roller through the circular track 35, the

lever arm remains at rest, though the cam continues to rotate.

The construction and operation of the switch mechanism is as follows:

5 Two switch points 37, 38 are pivoted on the cam at opposite ends of track 36. When point 37 directs the cam follower 27 into the inner track, the driven lever 25 is rocked to the right, then to the left as the follower leaves track 36. 10 The switch points 37, 38 are fastened to pins 39 and 40, respectively, passing through and journaled in the body of the cam 28. Levers 41 and 42 are fixed to pins 39, 40, respectively, and are interconnected by mechanism for moving the 15 points, which is next described.

For purposes of clarity, in Figs. 1 and 2, the cam body is shown in broken lines, the levers 41, 42, and the switching mechanism being drawn solid, whereas actually the levers are on the opposite face of the cam from the switch points and the cam tracks. Lever 41 of switch point 37 has pivoted to it a rod 43, which passes through the eye of a guide 44 fixed to the cam body. Rod 43 extends slidably through a bushing or sleeve 45 which is pivoted to the end of lever 25 of switch point 38. Beyond the sleeve a collar 46 presents an internal shoulder 47 which engages a shoulder on the rod 43. Collar 46 is slideable upon the reduced end portion of the rod and is urged yieldingly inward by a spring 48 bearing against a washer at the end of the rod.

A latch 49 is pivoted on the cam body, a spring 50 urges the latch normally into engagement with the collar 46, and a roller 51 on the latch is positioned to engage a movable abutment member 53 during rotation of the cam and release the latch.

Fig. 2 shows the switch point 37 open to pick up the cam roller 27 and direct it into the inner track 36. The latch 49 is released, and collar 46, lever 42, rod 43, and lever 41 have been moved to the left by the pressure of springs 48 and 52.

Fig. 1 shows the roller 27 leaving the inner cam track 36. As the cam rotates counter-clockwise 45 the roller 27 opens switch point 38, moving the switch lever 42 and sleeve 45 down against collar 46. This compresses spring 48 and urges the cam 28 down, drawing the switch point 37 closed and compressing the other spring 52. The spring 50 latch 49 engages the shoulder of collar 46 and holds switch point 37 closed. The cam roller 27 will therefore follow the circular track 35 and will impart no motion to the knife lever 25 until such time as point 37 is again opened and the 55 roller re-enters the eccentric track 36. On the

next revolution of the cam, the follower 27 engages the back of switch point 38 and closes it, sleeve 45 sliding up rod 43. On subsequent rotations of the cam the outer track 35 is unobstructed and operation is noiseless.

To trip the latch 49 and switch the follower 27 into the inner track 36, an abutment lever arm 53 is fixed to a machine shaft operable to move the arm into the position shown in Fig. 2 whenever operation of levers 26 and 25 is desired. In this position it lies in the path of travel of the roller 51 on the latch 49. When roller 51 engages it the latch is moved to release collar 46. The springs 48 and 52 then move the rod 43, collar 46, and switch lever arm 41 downward in Fig. 2, opening the switch 31. The cam follower 27 will then be directed into the inner track 36.

As the main shaft 23 rotates counter-clockwise the cam follower passes into the outer track (see Fig. 1) forcing the switch point 38 open. The switch lever 42 and its sleeve 45 move along rod 43, urging the collar 46 into a position where it will be re-engaged by the spring latch 49. Through spring 48 the rod 43 is urged endwise and closes the other switch point 37. This operation will be repeated each revolution of the cam so long as the abutment-engaging means 53 remains in the path of the latch abutment 51, or if the abutment-engaging means be moved out of the path of latch roller 51, the cam follower 27 will be directed into the circular track 35, where it will ride idle as described in the second paragraph above.

Certain details of construction in the mechanism as shown and described may be altered without departing from the invention as claimed herein. If desired, the circular idling track may be made smaller than the eccentric track and located within it, requiring only that the direction of swing of the switch points and the arrangement of their actuating mechanism be changed, without altering the essential operation of the invention.

An embodiment of the invention, so modified, is illustrated in Fig. 3 in which elements identical with those of the cam above described are given like reference numerals. The cam 28a has a circular idler track 55, with an eccentric track 56 outside of it. The cam roller 27 on rocker arm 26 follows the tracks and is actuated by the eccentric track to rock the lever arm 25. The switch points 57 and 58 are mounted at the ends of the eccentric track 56 on pins 59 and 63 respectively. The pins are journaled in and extend through the body of cam 28a. When the cam rotates counter-clockwise, as indicated by the arrow, the switch point 57 directs the follower alternatively into track 55 or track 56.

The mechanism for actuating and controlling the switch points, mounted on the opposite side of the cam, is shown in broken lines. Levers 61, 62 are fixed to pins 59 and 60, respectively. Lever 61 has pivoted to it a rod 63 slidable in a guide 64 fixed to the cam. Rod 63 is slidable also in a bushing 65 pivoted to the end of switch lever 62. A collar 66 bearing against a shoulder (not shown) on rod 63 is slidable on the reduced end portion of 63 and is urged to the left by coil spring 68 which bears against a stop washer at the end of the rod. A second spring 69 bears against guide 64 and the socket which pivotally connects rod 63 to lever 61.

A latch assembly comprising a latch 49 pivoted to the cam, a spring 50, and a roller 51, is constructed and operates like the latch assembly in Figs. 1 and 2. The roller 51 is positioned to engage the movable abutment member 53 on the associated machine and urge the latch out of engagement with the collar 66.

The operation is as follows: the points as shown in solid lines are positioned to direct the follower 27 through eccentric track 56 to rock the lever arm 25, the abutment lever 53 being in position to contact the latch roller 51. As the cam revolves the follower 27 will engage the outside of switch point 58, to close it across the idler track 55 in the position shown in dotted lines. This action will move lever 62 to the right into the position indicated in dotted lines, carrying the collar 66 to the right into engagement with the latch, compressing spring 68, and drawing rod 63 to the right. This in turn will rock lever 61 clockwise and open switch point 57, as indicated by dotted lines. On the next and subsequent revolutions of the cam the follower 27 will follow the circular idler track 55, opening point 58, which can be moved freely in this direction by reason of its lost motion connection with rod 63. The follower will continue to travel in this path unless and until the abutment member 53 is moved into position to trip the latch again.

Having described the construction and operation of the foregoing embodiment of my invention, what I claim and desire to secure by Letters Patent is:

35. 1. In a face cam, a circular idler track, an eccentric track opening at its ends into said circular track, a switch point at each end of said eccentric track between it and said idler track, pivotally mounted so that a cam follower can be 40 selectively directed during rotation of the cam to pass either through said eccentric track or said idler track, a connection between said switch points operable to close the leading switch point in response to displacement of the rearward 45 switch point by the cam follower passing out of the eccentric track to close the leading switch point across said eccentric track, resilient means normally urging said leading switch point open across said idler track to direct the cam follower 50 into said eccentric track, and spring latch means arranged normally to retain said leading switch point closed across said eccentric track, and an abutment on said latch means for engagement with abutment-engaging means movable to and 55 away from the path of travel of said latch abutment during rotation of the cam, said latch abutment operable on engagement with said abutment-engaging means to release said latch means to permit the leading switch point to close off 60 the idler track and open the eccentric track to direct the cam follower thereto.

2. The combination claimed in claim 1 wherein the rearward switch point has a lost-motion connection with the leading switch point, so that its motion is effective only to close the leading switch point across the eccentric track, its movement in the opposite direction in nowise affecting the situation of the leading point.
